UNITED STATES PATENT OFFICE.

EDWARD D. PRIEST, OF SCHENECTADY, NEW YORK, ASSIGNOR TO THE
GENERAL ELECTRIC COMPANY, OF NEW YORK.

DESIGN FOR A FIELD-MAGNET FRAME.

SPECIFICATION forming part of Design No. 29,372, dated September 20, 1898.

Application filed August 26, 1898. Serial No. 689,613. Term of patent 14 years.

To all whom it may concern:

Be it known that I, EDWARD D. PRIEST, a citizen of the United States, residing at Schenectady, county of Schenectady, State of New York, have invented and produced a new and original Design for Field-Magnet Frames for Dynamo-Electric Machines, (Case No. 894,) of which the following is a specification.

In the accompanying drawings, which illustrate my invention, Figure 1 is a perspective view of a dynamo-electric machine, and Fig. 2 is a cross-section of the same.

The leading feature of the design is the configuration of the field-magnet frame, substantially as shown in the drawings.

Referring by letter to the drawings, A represents the hollow field-magnet frame, which is divided into two parts A' and A''. The parts A' and A'' are bowl-shaped, and when closed, as shown in the drawings, form a chamber B. Extending rearwardly from one part of the frame are two supporting-lugs C

and C'. Situated on the sides of the casing and in line with each other are supporting-lugs D and D'. On one side of the frame is located a flat cover E, which covers an opening leading into the interior of the hollow frame.

By employing the configuration of field-magnet frame as set forth above I am enabled to make a dynamo-electric machine which is compact and at the same presents a pleasing appearance.

I claim—

The design for a field-magnet frame for a dynamo-electric machine, substantially as shown and described.

In witness whereof I have hereunto set my hand this 23d day of August, 1898.

EDWARD D. PRIEST.

Witnesses:

A. F. MACDONALD,
A. H. ABELL.
